UNITED STATES PATENT OFFICE.

NIELS W. JENSEN, OF NORTH TROY, NEW YORK, ASSIGNOR TO S. AND R. FOLDING MACHINE COMPANY, OF COHOES, NEW YORK, A CORPORATION OF NEW YORK.

TOOL FOR FOLDING SHIRT NECKBANDS.

Application filed February 20, 1923. Serial No. 620,152.

Among the principal objects which the present invention has in view are: to provide means for facilitating the seaming of the raw edge of the collar bands; to facilitate the folding of the material preparatory to forming the same; to operate in the manner mentioned on collars constructed by weaving special fashioned collar bands having partial and complete multi-ply sections and particularly to fold the cut ends of collar bands formed by severing band sections from a continuously woven fashioned strip having solid double woven and thin single woven selvaged edges for sewing each band in service position upon a shirt; and to simplify and cheapen the construction of the apparatus.

Drawings.

Figure 1 is a side view of a severed section for forming a collar band.

Figure 2 is a perspective view of the apparatus employed for folding the severed ends of the collar band preparatory to sewing and inverting the same.

Figure 3 is a top plan view of the apparatus.

Figure 4 is a side view of the apparatus showing in conjunction therewith a fragment of a collar band section for the handling of which the apparatus is especially designed.

Figures 5, 6 and 7 show fragments of the collar band illustrating the three phases of the development of the construction to the completed commercial article.

Description.

As shown best in Fig. 1 of the drawings 40 collar bands for operating upon which the herein disclosed apparatus is designed are woven to form a continuous strip having the edges 12 and 13 straight, while the edge 14 forms a succession of curves shaped to 45 conform with the desired bands for collars of men's shirts. The harness supporting certain of the web threads of the loom is disposed in position so that all of the threads are locked by the shuttle thread or woof to 50 form solid body sections 15. The harness which supports the web threads adjacent the edges 12 and 13 are, however, shifted into play alternately with the result that the material adjacent the edges 12 and 13 is woven

as a lighter material, the sections of which 55 overlie or rest upon each other.

As seen in the drawings in Figure 1, the spaces between the portion 16 and the edges 12 and 13 are the single woven sections or sections employing half of the web threads 60 in the loom. The result is that the sections 15 are close or tightly woven, the threads being drawn close with the result that the fabric is at this portion semi-stiff requiring substantially no starching when laundered. 65

To form pocket sections in the collar band for receiving a button-hole and the collar button used therein the solid portions 15 are terminated and spaced apart from the double ply portion 16. The portion 16 is formed 70 by weaving the two sides forming the said portion 16 as in the same manner as that employed for forming sections adjacent the edges 12 and 13, or in other words, during the weaving of this section the web threads 75 are alternately placed in position to receive the woof or shuttle thread.

When weaving collar bands of the nature referred to the end sections 17 are constructed in a manner described as to the portion 80 16. The continuous strip is in reality a succession of collar band sections. These are made according to various lengths of collar bands and the individual bands are severed from the continuous strip by cutting 85 through the sections 17. The result is that the extreme ends of the severed bands are left raw. It becomes necessary to close these ends with a seam and it is desired that the seam shall be turned in within the collar 90 band structure. To assist in the accomplishment of this the apparatus herein disclosed is employed.

As seen in the drawings an upright shaping horn 18 is mounted on a base plate 19. 95 The base plate 19 is secured by suitable fastening devices such as the screws 20 on a table as indicated by the numeral 21. The horn 18 is preferably constructed of sheet metal bent upon itself to provide between 100 the sides thereof a slightly flared edge opening channel 22. The base plate 19 has cut therein an edge opening slot 23 which conforms with the channel 22 of the form 18. The upper extremity of the form 18 has 105 edges 24 inclined at an angle of approximately 45 degrees which upwardly terminate in shapely round corners 25.

- In practice the channel 22 and slot 23 receive the body of the collar band which is drawn downward until the corners 25 coincide with the portion of the sections 17 marking the length of the collar band. The collar band then being held the operator easily folds back over the shaping horn so much of the material constituting the section 17 as will rest upon the inclined edges 24. 10 The section 17 having been folded back in this position, the collar band and said section are removed from the horn 18 lifting the collar band upward in removing it from the channel 22. The section 17 is now in position to be pressed and when pressed is sewed as indicated by the line of stitching 26 in Figure 6 of the drawings.

The seam formed by the stitching 26 having been made, the end of the collar is now 20 inverted so that the raw edge of the collar is turned in or held between the sides forming the section 17.

It will be understood that a button-hole 25 is placed in the section 17 which thereafter joins the two sides, or two-ply of which this section is constructed while the edges 12 and 13 at the bottom of the collar band being stitched firmly to the edge of the body

of the shirt close the section 17 permanently and securely.

Claims.

1. A tool for folding shirt neck bands comprising a shaping horn having an elongated body, the sides whereof form an edge opening channel; and means for mounting said horn in stationary service position, said means embodying a base plate rigidly connected with said horn and having an edge opening slot therein conforming with the channel in said horn. 35

2. A tool for folding shirt neck bands comprising a base plate having an edge opening slot therein with inwardly converging sides, a shaping horn rigidly mounted 45 on said base plate and rising vertically therefrom, said horn consisting of a metal blank bent upon itself to form an edge opening channel with inwardly converging side walls registering with the slot of said base plate, the upper ends of said side walls being downwardly inclined from the bend of said horn to the side wall edges with the peak of the horn being rounded off. 50
